CARTON FOR PACKAGING AND DISPLAYING ARTICLES

Swan Hillman, Rockford, Ill.

Application November 6, 1953, Serial No. 390,484

5 Claims. (Cl. 206—45.2)

This invention relates to cartons for packaging articles of merchandise and, more particularly, to cartons which may be opened and reassembled to form a unit for displaying the merchandise.

The general object of the invention is to provide a new and improved carton of the above character which is inexpensive to manufacture, which is easy to assemble for both packaging and display purposes and which forms not only a secure package but also a neat and attractive display.

Another object is to make the carton in two similar parts which are triangular in shape and mate with each other to form a package enclosing the merchandise and which may be reassembled to form a display simply by removing one half and placing it under the second half to tilt the latter up at an angle, the exposed merchandise remaining in the second half and also being tilted so that it may be viewed more easily.

A more detailed object is to use two right triangular halves which form a rectangular carton and which are held together both as a packaging carton and as a display unit by means of novel fastening elements.

Other objects and advantages of the invention will become apparent from the following detailed description taken in connection with the accompanying drawings, in which

Figure 1 is a perspective view of a carton embodying the novel features of the present invention.

Fig. 2 is a perspective view showing the parts of the carton separated.

Fig. 3 is a perspective view illustrating the manner in which the parts are assembled to form a display unit.

Fig. 4 is a perspective view of several assembled display units.

Fig. 5 is a sectional view taken along the line 5—5 in Fig. 1.

Fig. 6 is a plan view on a reduced scale of a sheet of cardboard from which a part of the carton is made.

Fig. 7 is a top view of the carton with parts broken away and shown in section.

As shown in the drawings for purposes of illustration, the invention is embodied in a carton 10 for packaging and displaying merchandise, such as screws and the like, which may be contained in transparent plastic boxes 11. The latter, when shipped to the retailer, are enclosed by the carton which preferably is of rectangular shape and comprises top, bottom, side and end walls 12, 13, 14, 15 and 16. Cartons of this type may conveniently be arranged to be opened and reassembled in such a manner as to form a display with the boxes 11 exposed so that the merchandise may be seen by the consumer.

The present invention contemplates the provision of a novel carton which is comparatively inexpensive to manufacture, which is simple both to assemble for shipment and to reassemble for display, and which provides a neat and attractive display while permitting the boxes 11 to be removed easily. To these ends, the carton is

2

composed of two similar halves or boxes 17 and 18 which are triangular in shape and fit together to form an enclosure in which the plastic boxes 11 are packaged. The carton is opened by removing the upper half 17 while leaving the boxes stacked in the lower half 18 and exposed to view and the upper half then is placed under the lower half to act as a wedge which tilts the lower half and hence the boxes up at an angle to form the display.

10 In the present instance, the two carton halves 17 and 18 are identical and are right triangular in shape so that, by placing the diagonal edges 19 (Fig. 2) of the halves together as shown in Fig. 1, the latter form a rectangular carton for enclosing the boxes 11. When the upper half 17 is removed, the boxes are uncovered as illustrated in Fig. 2 and thus may be left in the lower half 18 when displayed to the consumer. In order that the consumer sees the tops of the boxes and readily views the merchandise inside, the upper half is placed on its diagonal edge new 20 (Figs. 3 and 4) whereby the top wall 12 on this half is inclined and the lower half is mounted on the upper half with the bottom wall 13 on the top wall 12 so that the two halves form a parallelogram and the boxes are tilted up at an angle.

25 Each carton half is made of cardboard or the like and is composed of two right triangular side panels with the two perpendicular edges of one panel joined to the corresponding edges of the other panel by rectangular walls. The upper half 17, for example, comprises spaced 30 and parallel triangular side panels 20, a rectangular wall 12 which joins the longer edges of the side panels and forms the top wall of the carton, and a second rectangular wall 15 joining the shorter edges of the panel to form the carton end wall. This half may be made from a single flat sheet 21 of cardboard cut to the shape shown in Fig. 6. The sheet is folded along the lines 22 between the top wall 12 and the side panels 20 and then the parts 23 and 24, which together constitute the end wall 15, are folded in along the lines 25 so that 35 one overlies the other as shown in Fig. 7. The two end wall parts are pasted or otherwise secured together to retain the folded shape of the half. The lower half 18 is similarly formed by triangular side panels 20 and the rectangular end and bottom walls 16 and 13 and also is folded from a single sheet like that in Fig. 6.

40 Means is provided for attaching the lower half 18 to the upper half 17 when the latter is acting as a wedge so that the two halves are held together as a rigid display unit. This means comprises a fastening element 27 which

45 is a part of one half and engages the other half to lock the two halves together and prevent the lower half from sliding on the inclined wall 12. Preferably there is a fastening element on each half and the two fastening elements are at opposite ends of the carton to obtain optimum rigidity. Herein, each fastening element 27 is 50 a tab projecting from one half and received in a slot 28 in the other half. The tabs 27 may, as illustrated, be extensions of the longer walls of the carton halves, that is, the top wall 12 on the upper half and the bottom wall 13 on the lower half, and are joined to these walls by fold lines 29 (Fig. 6).

55 The slots 28 for receiving the tabs 27 are in the ends of the walls 12 and 13 at the intersection of these walls and the end walls 15 and 16 respectively and extend 60 transversely of the carton halves. Conveniently, the slot in the top wall 12 may be formed by cutting away the end of the wall in the sheet 21 as indicated at 30 (Fig. 6) so that the wall stops short of the ends of the triangular side panels 20 leaving a space between the top wall and the end wall 15 when the sheet is folded, the slot in the bottom wall 13 being formed in the same 65 manner.

With the foregoing arrangement, the tab 27 on the lower half 18 is over the slot 28 on the upper half 17 when the two halves are placed together to form the display (see Fig. 3) and the tab is bent down and inserted into the slot to lock the halves together. Similarly, at the other end of the display unit, the tab on the half 17 is bent up and into the slot in the half 18.

Preferably, the tabs 27 also are effective to hold the two carton halves 17 and 18 together when the latter form the rectangular packaging carton 10. For this purpose, each carton half is formed with a slot 31 in the outer end of the corresponding end wall 15 or 16 where it is in position to receive the tab on the other half when the two halves are placed together with their diagonal edges 19 abutting against each other. Herein, the slot 31 is defined by the two parts 23 and 24 of the end walls, these parts being pasted together only a portion of the distance from the corner of the half. In this way, the ends of the parts 23 and 24 may be separated and the tab 27 inserted between them as shown in Fig. 5.

When the carton 10 is assembled for shipping with the tabs 27 received in the slots 31, the two halves 17 and 18 are prevented from separating by a band or sheet 32 of paper or the like wrapped around the carton so as to overlie the side walls 14 and the top and bottom walls 12 and 13. To open the carton, the band 32 is cut along the diagonal edges 19 of the carton halves so that the upper half may be removed. Such cutting is facilitated by recessing the intermediate portions of the diagonal edges as indicated at 33 (Fig. 2) and, when the halves are placed together, the recesses form a slot 34 (Figs. 1 and 5) into which a knife or other cutting tool may project.

If desired, each of the halves 17 and 18 may be used individually to display the plastic boxes 11. In this case, the half is disposed with the end wall 15 (in the case of the half 17) facing down and the top wall 12 upright and against a wall of the room. The half is hung in this position on the wall such as by a nail projecting through a hole 35 in the tab 27. The boxes 11 then are stacked in the half and rest on the wall 15.

It will be observed that the carton halves 17 and 18 not only form an effective enclosure for shipping merchandise but also may be assembled as a neat and attractive unit for displaying the merchandise. When assembled either as a packaging carton or a display unit, the halves are held together securely by the tabs 27. At the same time, the carton is comparatively inexpensive since both halves may be identical in construction. Different types of displays may be formed by employing two or more cartons at the same time. For example, several display units may be used together and arranged side by side in a row as shown in Fig. 4 to form a larger display or to present a wider variety of merchandise.

I claim as my invention:

1. A display carton comprising two boxes of the same size and right triangular shape formed separately from each other and each open along its diagonal and closed along first and second sides opposite the diagonal, said boxes abutting each other along said first sides and forming a tilted display carton shaped as a parallelogram open at the top and the bottom, a flap formed as an extension of said first side of each box at the acute angle end of the side, and means on each box defining a slot opening outwardly adjacent the right angle corner of the box and receiving said flap of the other box thereby holding the boxes assembled releasably together in said parallelogram with the flaps concealed on the interior of the boxes.

2. A display carton comprising two boxes of the same size and right triangular shape formed separately from each other and each open along its diagonal and closed along first and second sides opposite the diagonal, said boxes abutting each other along said first sides and forming a tilted display carton of parallelogram shape open at the top and the bottom, and a set of fastening devices holding said boxes together with said first sides thereof in abutment and comprising a tab integral with one box and means on the other box releasably receiving the tab.

5 3. A display carton comprising two separate boxes of the same size and right triangular shape each open along its diagonal and closed along first and second sides opposite the diagonal, said boxes abutting each other along said first sides and forming a tilted display carton shaped as a parallelogram open at the top and the bottom, and a set of fastening elements formed integral with said boxes and interfitting releasably with each other, said fastening elements holding the boxes together in said 10 carton while permitting separation of the boxes and rearrangement of the same with their diagonals abutting to form a rectangular shipping carton.

15 4. A shipping carton comprising two separate boxes of the same size and right triangular shape each open along its diagonal and closed along first and second sides opposite the diagonal, said boxes abutting each other along said diagonals and forming a closed rectangular carton, means on each box defining a slot adjacent each 20 end of said second side of the box, and a tab formed on each box adjacent the acute angle end of said first side of the box and fitting releasably into a first one of said slots of the other box thereby holding the boxes assembled together, said tab of each of said boxes being removable from said first slot of the other box and adapted to fit 25 into the other of the slots of the other box whereby to hold the boxes assembled together as a display carton of parallelogram shape after separation and rearrangement of the boxes to bring said first sides into abutment with each other.

30 5. A shipping carton comprising two separate boxes of the same size and right triangular shape each open along its diagonal and closed along first and second sides opposite the diagonal, said boxes abutting each other along their diagonals and forming a closed rectangular shipping carton, and fastening means on each of said boxes 35 engaging the other box and holding the boxes assembled together, said fastening means including a tab projecting from said first side of each box adjacent the acute angle end of the side and a slot opening outwardly adjacent the right angle corner of the box and adapted to receive said tab of the other box whereby to hold the boxes releasably assembled as a display carton of parallelogram shape after separation and rearrangement of the boxes to bring said first sides into abutment with each other.
